UNITED STATES PATENT OFFICE.

FREDERIC E. BERTRAND, OF LYNN, MASSACHUSETTS, AND PEARL J. WENTWORTH, OF NEWPORT, KENTUCKY, ASSIGNEES, BY MESNE ASSIGNMENTS, TO UNITED SHOE MACHINERY CORPORATION, OF PATERSON, NEW JERSEY, A CORPORATION OF NEW JERSEY.

SHOE-BEATING MACHINE.

1,331,797.

Specification of Letters Patent. Patented Feb. 24, 1920.

Application filed February 26, 1916. Serial No. 80,612.

To all whom it may concern:

Be it known that we, FREDERIC E. BERTRAND and PEARL J. WENTWORTH, citizens of the United States, residing at Lynn, in the county of Essex and Commonwealth of Massachusetts, and Newport, in the county of Campbell and State of Kentucky, respectively, have invented certain new and useful Improvements in Shoe-Beating Machines; and we do hereby declare the following to be a full, clear, and exact description of the invention, such as will enable others skilled in the art to which it appertains to make and use the same.

15 This invention relates to beating machines for beating out the bottom portions of shoes.

In the manufacture of welted shoes the feather of the insole is often bent or turned 20 to a considerable degree away from the plane of the body of the insole after the inseam is sewn. The feather pressing against the inside of the upper above the inseam gives the proper bulge or overhang to the 25 upper, and determines to a great degree the shape of the shoe, and the undue bending of the feather away from the plane of the body of the insole gives the shoe an irregular and unfinished appearance.

30 The primary object of the present invention is to produce an improved and efficient shoe beating machine by which the welt and the feather of the insole may be beaten out and set substantially in the plane of the 35 body of the insole quickly and easily in one operation.

With this object in view the invention consists in the novel and improved constructions, arrangements and combinations of 40 parts hereinafter described and pointed out in the claims, the advantages of which will be obvious to those skilled in the art.

The novel features of the invention will be readily understood from an inspection of 45 the accompanying drawings illustrating a machine embodying the invention in its preferred form and the following detailed description.

In the drawings, Figure 1 is a view in side 50 elevation of the machine with certain parts shown in section;

Fig. 2 is a view in front elevation of the lower portion of the machine;

Fig. 3 is a view in vertical section of the lower forward portion of the machine;

Fig. 4 is a detail view in side elevation illustrating the horn and associated parts;

Fig. 5 is a detail plan view illustrating the upper portion of the horn; and

Fig. 6 is a sectional view taken substantially on the line 6—6 of Fig. 3.

The machine illustrated in the drawings is provided with a welt support 2 shaped to enter the crease between the welt and upper of a lasted shoe and support the welt upon its upper surface, and with a feather support or table 4 having its upper surface substantially parallel with the upper surface of the welt support and adapted to engage the inner face of the marginal portion 70 of the insole to support the feather in substantially the plane of the body of the insole. The machine is also provided with a hammer 6 arranged to extend over the welt and the marginal portion of the insole when 75 the shoe is placed in operating position in the machine.

The beating hammer 6 is fixed to the lower end of a hammer rod 8 mounted for vertical reciprocation in guides in the forwardly projecting arms 10 and 12 formed on the frame of the machine. The hammer rod is reciprocated by the movement of a sleeve 14 mounted on the hammer rod and connected by a link or pitman 16 with a 80 crank 18 on the hammer operating shaft 20 mounted in a suitable bearing in the frame. In order to cushion the blows delivered by the hammer, a coiled spring 22 surrounding the hammer is interposed between the sleeve 90 14 and a collar or nut 24 on the hammer rod. The downward movement of the hammer rod in the sleeve 14 is limited by the engagement of the upper end of the sleeve 95 with a collar or nut 26 on the rod.

The welt support 2 consists of a rotary table mounted on the forward end of a bar 28 secured to a pivoted carrier 30. The carrier 30 is pivoted upon a shaft 32, and rests at its rear end against the cam face 34 100 of an abutment 36 pivoted on the shaft 38. The abutment 36 is normally held in forward position as illustrated in dotted lines in Fig. 1, by means of a coiled spring 40 secured at its ends respectively to the carrier 105 30 and to the abutment. The cam face 34

- is formed on a gradually increasing radius from the rear to the forward portion of the abutment, so that by swinging the abutment from the position shown in dotted lines rearwardly to the position shown in full lines in Fig. 1 the welt support will be raised. The raising of the welt support increases the pressure of the hammer on the welt, and enables the refractory portions of the welt to be beaten out more readily. The abutment 36 is swung in a direction to raise the welt support by means of a treadle (not shown) connected with the abutment by means of a treadle rod 42. The movement of the abutment in a direction to raise the welt support is limited by the engagement of an adjustable abutment screw 44 mounted in an arm 44' formed on the abutment 34 with a projection 46 on the frame.
- 20 The feather support 4 is mounted on the upper end of the rotatable horn 48 similar to the horn employed on certain classes of shoe sewing machines. The horn is provided with a cylindrical shank 50 which is adapted to be clamped in a bore in the clamping arm 52 of the horn carrier 54 by means of a clamping bolt 56. By loosening the clamping bolt the horn is unclamped and may then be adjusted vertically in the arm and clamped in adjusted position. The horn carrier 54 is pivoted upon the vertical shaft 58 so that the horn may be turned as the different parts of the welt and the margin of the insole are presented to the action of the beating hammer. The horn carrier is held on the shaft 58 by means of a cap plate 60 secured to the upper end of the shaft. In order to enable the shoe to be placed in position with the horn within the shoe and the feather support engaging the lower face of the margin of the insole and the welt support underlying the welt, the horn is mounted upon a horizontal axis to swing forwardly away from the welt support. The shaft 58 is carried by and preferably formed integral with a hanger 62 mounted on the shaft 64 carried by the forwardly projecting arms 66 on the frame of the machine. The horn is normally held in operating position by spring controlled mechanism acting on the hanger 62. The hanger 62 is formed with a forwardly projecting arm 68 which engages in the loop end of a U-shaped wire 70 passing through the compression spring 72, and having its out-turned ends engaging one end of the spring. A similar U-shaped wire 74 passing through the coiled spring has its out-turned ends engaging the opposite end of the spring, and receives in its loop end a pin 76 mounted at the end of a yoke shaped lever 78, the arms of which are fixed to trunnions 80 mounted to turn in bearings in the forwardly projecting arm 82 on the frame. A gear segment 84 is fixed to one of

the trunnions 80, and has its teeth in mesh with the teeth of a rack bar 86 attached to the hanger 62. The parts are constructed and arranged so that when the horn is in its normal or operating position the connections between the arm 68 and the pin 76 lie above the axis of the lever 78, and the coiled spring 72, through its action directly upon the hanger 62 and through its tendency to turn the lever 78, tends to swing the hanger 62 rearwardly. The rearward swinging movement of the hanger is limited by the engagement of an adjustable abutment screw 88 threaded into the arm 90 on the frame with an abutment 92 on the hanger. The spring 72 during the operation of the machine constantly tends to swing the hanger toward the rear of the machine, and thus keeps the horn in operating position. The yielding of the spring 72 allows the feather support to yield relatively to the welt support to accommodate different thicknesses of upper material between the two supports.

When a shoe is to be removed from the horn, or a shoe is to be placed in position on the horn, the horn is swung forwardly by the operator out of operating position. During the first part of the forward swinging movement of the horn, or until the connections between the arm 68 and the pin 76 cross the axis of the lever 78, the spring 72 is compressed, and the swinging movement of the arm takes place against the tension of the spring. After these connections pass the axis of the lever 78 the spring tends to turn the lever in a direction to swing the hanger 62, forwardly on the shaft 64. After a shoe has been placed on the horn the operator swings the horn upwardly and rearwardly toward its operating position. The first part of this movement takes place against the tension of the spring 72, but after the connections between the arm 68 and the pin 76 pass the axis of the lever 78, the spring throws the horn rearwardly into operating position.

The feather support 4 is formed at its rear margin with an edge of a comparatively large radius of curvature, so that it will support a section of the feather of considerable length in an efficient manner against the blows of the hammer. The feather support is pivoted on the upper end of the horn to turn upon an axis substantially coincident with the axis of the horn, and mechanism is provided for maintaining the feather support in a substantially unvaried angular position during the turning movements imparted to the horn as the point of operation is transferred about the shoe, to keep the feather engaging margin of the feather support in unvaried relation to the welt support and the beating hammer throughout the beating operation. The

feather support is fixed to the upper end of a shaft 94 journaled in the upper end of the horn. A bevel gear 96 is fixed to the lower end of the shaft, and meshes with a bevel gear 98 mounted to turn in the upper end of the horn. A second bevel gear 100 is fixed to the bevel gear 98 and meshes with a bevel gear 104 mounted on the upper end of a shaft 106 journaled in the horn. This shaft carries at its lower end a bevel gear 108 meshing with a bevel gear 110 mounted on one end of a shaft 112 journaled in the horn, to the other end of which is fixed a bevel gear 114 meshing with a bevel gear 116 mounted on the upper end of the vertical shaft 118 journaled in the cylindrical shank of the horn. To the lower end of this vertical shaft is fixed a spur gear 120 meshing with a small spur gear 122 journaled on the pin 124 secured in the horn carrier 54, which gear in turn meshes with a stationary spur gear 126 fixed to the stationary shaft 58 upon which the horn carrier turns. The series of gears above described intermediate the feather support 4 and the stationary gear 126 are so proportioned that the feather support 4 will be kept in a stationary position during the rotary movements of the horn. The result is that the marginal portion of the feather support having a curved edge of large radius is maintained in position opposite the welt support and beneath the beating hammer as the horn is rotated in presenting the different portions of the welt and insole to the action of the hammer.

Having explained the nature and object of the invention, and having specifically described one form of machine in which it may be embodied, what is claimed is:—

1. A shoe beating machine having, in combination, a welt support and an insole support relatively located so as to support the welt and the marginal portion of the insole and constructed to permit the shoe to be moved relatively thereto to advance the welt and the insole across the work supporting faces thereof, and beating mechanism arranged to beat out the welt and the feather of the insole as they are advanced across said supports.

2. A shoe beating machine having, in combination, a welt support and an insole sup-

port relatively located so as to support the welt and the marginal portion of the insole, 55 and constructed to permit the shoe to be moved relatively thereto to advance the welt and the insole across the work supporting faces thereof, and a single beater arranged to beat out simultaneously the welt and 60 feather of the insole as they are fed across said supports.

3. A shoe beating machine, having, in combination, a welt support a support for the feather of the insole, beating mechanism for 65 beating out the welt and the feather, and means whereby the welt support and the feather support may be independently adjusted to vary the pressure of the beating- 70 mechanism on the welt and the insole.

4. A shoe beating machine, having, in combination, a welt support, a support for the feather of the insole, beating mechanism for beating out the welt and the feather, a horn upon which the feather support is 75 mounted, a shaft upon which the horn is pivoted to swing into and out of operating position, and means for holding the horn in operating position.

5. A shoe beating machine, having, in 80 combination, a welt support, a support for the feather of the insole, means for beating out the welt and the feather, a rotary horn upon which the feather support is pivoted, and means for maintaining the feather sup- 85 port in unvaried angular position during the rotary movements of the horn.

6. A shoe beating machine, having, in combination, a welt support, a support for the feather of the insole arranged to engage 90 the marginal portion of the insole within the shoe and to permit the shoe to be moved to advance the insole across the work supporting face thereof, and beating mechanism for beating out the welt and the feather. 95

7. A shoe beating machine, having, in combination, a welt support, a support for the feather of the insole arranged to engage the marginal portion of the insole within the shoe and to permit the shoe to be moved to 100 advance the insole across the work supporting face thereof, and a single beater for simultaneously beating out the welt and the feather.

FREDERIC E. BERTRAND.
